Primary Examiner—Melody N. Brown

(57) **CLAIM**

The ornamental design for a cargo box surface, as shown and described.

DESCRIPTION

FIG. 1 is a left rear elevated perspective view of a cargo box surface showing our new design.

FIG. 2 is a top plan view of the cargo box surface design of FIG. 1.

FIG. 3 is a left side view of the cargo box surface design of FIG. 1.

FIG. 4 is a right side view of the cargo box surface design of FIG. 1.

FIG. 5 is a rear view of the cargo box surface design of FIG. 1.

FIG. 6 is a left rear elevated perspective view of a cargo box surface showing a second embodiment of our new design.

FIG. 7 is a plan view of the cargo box surface design of FIG. 6.

FIG. 8 is a left side view of the cargo box surface design of FIG. 6.

FIG. 9 is a right side view of the cargo box surface design of FIG. 6; and,

FIG. 10 is a rear view of the cargo box surface design of FIG. 6.

The broken lines shown in FIGS. 1, 2, 6, and 7 are shown for illustrative purposes and form no part of the claimed design.

1 Claim, 4 Drawing Sheets
